(57) **CLAIM**

We claim the ornamental design for a pet collar, as shown and described.

DESCRIPTION

FIG. 1 is a top, front, right perspective view of a pet collar, showing our new design;

FIG. 2 is a top, rear, right side perspective view thereof;

FIG. 3 is a top, rear, left side perspective view thereof;

FIG. 4 is a top plan view thereof;

FIG. 5 is a bottom plan view thereof;

FIG. 6 is a left side elevation view thereof;

FIG. 7 is a right side elevation view thereof;

FIG. 8 is a rear elevation view thereof;

FIG. 9 is a front elevation view thereof;

FIG. 10 is an enlarged top, front, right side perspective view of the buckle;

FIG. 11 is an enlarged bottom, front right side perspective view thereof;

FIG. 12 is an enlarged rear elevation view thereof;

FIG. 13 is an enlarged front elevation view thereof;

FIG. 14 is a second enlarged bottom, front, right side perspective view thereof;

FIG. 15 is a second enlarged top, front, right side perspective view thereof;

FIG. 16 is an enlarged top plan view thereof;

FIG. 17 is an enlarged bottom plan view thereof;

FIG. 18 is an enlarged rear elevation view thereof;

FIG. 19 is an enlarged front elevation view thereof; and,

FIG. 20 is an enlarged rear, bottom perspective view thereof.
